UNITED STATES PATENT OFFICE.

JOHN D. LYLE, OF COLUMBUS, INDIANA.

TELEPHONE-SWITCH.

SPECIFICATION forming part of Letters Patent No. 309,791, dated December 23, 1884.

Application filed July 10, 1884. (No model.)

To all whom it may concern:

Be it known that I, JOHN D. LYLE, a citizen of the United States, residing at Columbus, in the county of Bartholomew and State 5 of Indiana, have invented certain new and useful Improvements in Telephone-Switches; and I do hereby declare the following to be a full, clear, and exact description of the invention, such as will enable others skilled in 10 the art to which it appertains to make and use the same.

This invention consists of a switch for telephone - stations, composed of a fixed hook adapted to hold the telephone-receiver, and a 15 sliding spring - actuated commutator which projects into said hook.

In order that my invention may be clearly understood, I have illustrated in the annexed drawings, and will proceed to describe, a practical form thereof, and a mode of applying it 20 to a local telephone-station.

Figure 1 is a perspective view of my improved switch for telephones. Fig. 2 is a diagram illustrating a mode of applying such 25 switch to a terminal local telephone-station.

The same letters of reference indicate identical parts in all the figures.

The sliding commutator A, mounted on a suitable board, A', is in permanent electrical 30 connection with the contact-spring F, with which the line-wire L is connected. It is provided with a contact-point, b, adapted to make contact with contact-spring B, which is connected with one side of the bell-magnet, the 35 other side of which is connected to earth. The commutator is provided with three other contact-points, c d e, adapted to simultaneously make contact with the contact-springs C, D, and E, respectively. Contact-spring C 40 is connected with one end of the secondary coil of the inductorium I, the other end of said coil being connected with one side of the electro-magnet of the receiver R, the other side of which is connected to earth. Contact-springs D and E are the terminals of the in- 45

ductorium's primary circuit, which includes the transmitter T. The commutator is arranged to slide on a couple of studs which pass through longitudinal slots in the commutator, as clearly shown. A spring, G, 5 holds the commutator in the position shown in the drawings, so that one end of it is projected into the hook H when the receiver is detached from the said hook. In that position of the commutator it is in electrical connection with the contact-springs C D E, so that the primary circuit of the inductorium is closed and its secondary coil put in the line-circuit, the connection between the commutator and contact-spring B being broken, so 6 as to cut out the bell-magnet.

In placing the receiver in hook H the commutator is pushed back, and its points c d e break from the contact-springs C D E, while its point b makes contact with contact-spring 6 B, putting the bell-magnet in the line-circuit.

I am aware that telephone-switches are known in which a switch-lever is so arranged with reference to a fixed hook for supporting the telephone that said telephone cannot be 7 taken from the hook or replaced upon it without turning the switch-lever and changing the circuit-connections; but I believe that I am the first to construct a telephone-switch with a sliding spring-actuated bar which is projected by its spring into the supporting-hook when the telephone is detached, and pushed back by the telephone in placing it in the hook.

I claim as my invention—
The combination, substantially as before set forth, of the fixed hook for supporting a telephone-receiver, and the sliding spring-actuated commutator projecting into said hook.

In testimony whereof I affix my signature in 8 presence of two witnesses.

JOHN D. LYLE.
